UNITED STATES PATENT OFFICE.

GEORGE K. HUNDLEY, OF COVINGTON, KENTUCKY.

FARE-BOX.

1,278,933.

Specification of Letters Patent. Patented Sept. 17, 1918.

Application filed October 13, 1917. Serial No. 196,386.

To all whom it may concern:

Be it known that I, GEORGE K. HUNDLEY, a citizen of the United States, and a resident of Covington, in the county of Kenton and State of Kentucky, have invented certain new and useful Improvements in Fare-Boxes, of which the following is a specification.

My invention relates to deposit and collection receptacles, and its object is to provide self-contained means for the safe collection of coins of different denominations, and, by combination of the invention with a separate and distinct fare registering mechanism, to register the amounts of coins collected of one denomination.

My invention consists in the combination of parts and in the details of construction and arrangement of parts as will herein be more fully described and claimed.

In the drawing:

Figure 1 is a general perspective view showing my invention in combination with part of the fare registering mechanism of a street car;

Fig. 2 is a sectional perspective view of the upper part of the device embodying my invention, the section being on a plane corresponding to the line 2—2 of Fig. 1; and

Fig. 3 is a vertical cross-sectional elevation, the section being on a plane corresponding to the line 3—3 of Fig. 2.

As I prefer to construct my invention, it comprises a box or casing 1 having horizontally across its interior, a partition 2 dividing it into an upper compartment 3 and a lower compartment 4. On the top of the box 1 is a raised part 5 backed by the fare designating placard 6, and having down through its top near one end the coin slot 7. The chute 8 leads downwardly and to the left and terminates in the magazine 9 which is in the form of an upright tube supported on a horizontal guideway 10 with a slotted slide 11 sliding in the guideway 10 under the magazine 9. The bottom of the chute 8 up near where it curves down from the slot 7, has in its an opening 12 of width less than the total width of the interior of

the chute 8, and opening downwardly into a hopper 13 that inclines toward the rear of the casing 1 to deliver a coin falling from the opening 12 to the upper side of a trap-door 14 that normally is held up to close an opening 15 in the horizontal partition 2 by means of a weighted arm 16 outside the

rear of the box and fixed on the rod 17 that forms the hinge pivot of the trap-door 14. The lower compartment 4 contains the drawer or receptacle 18 which may be removed through the rear of the compartment 4 when a door 19 hinged on the rear wall of the box 1 is opened and which door is normally held closed by a seal 20 (Fig. 1).

Shortly to the rear of the lower end of the magazine 9, a lower chute 21 leads from the interior of the guideway 10 upwardly and to the right and opens through the back of the box 1 into a cup 22 fixed on the outside of said back.

The horizontal shaft 23 journaled in a bracket 24 that extends up and straddles one of the rafters of the car roof is, it will be understood, the shaft that operates the fare register on the car, which may be, for instance, like that shown in United States Patent No. 624,091, of May 2, 1899, and which mechanism not forming part of my invention need not be shown herein; it being sufficient to describe that a short arm 25 fixed on the shaft 23 within the bracket 24 is pivoted to a rod 26 that runs down through the tubular post 27, the upper end of which is fixed to the lower side of the bracket 24 and the lower end of which is fixed in a pedestal 27' on the floor of the car; and to describe that a treadle 28 suitably pivoted in the pedestal, or a lever 29 suitably pivoted in the post 27 at a convenient height, serves for raising the rod 26 either by the foot or by the hand, and a consequent partial turning of the shaft 23 sufficient to operate the fare register.

The box or casing 1 containing the structure of my invention just described, is mounted preferably upon a suitable bench or pedestal 30 that rests on the car floor in such a position relative to the post 27 that said post 27 and the magazine 9 and its slide 11 are on a single line from front to rear of the structure; and so that the back of the casing 1 is very close to the post 27. A bracket 31 extends forward from the post 27 into the box or casing 1 just below the horizontal partition 2 and carries the fulcrum for a bell-crank 32 with an arm extending up and connected by a link 33 to a downwardly extended lug 34 on the rear end part of the slide 11; and having an arm extending down to the rear with a head 35 extending into a slot 36 in the rod 26 through a slot 37 in the post 27.

The slot 38 in the slide 11 is preferably considerably longer than the coin, and the parts are so proportioned that when the rod 26 is in its lowermost or normal position, 5 the slot 38 lies over the entrance to the lower chute 21 and the slide 11 has the solid part under the lower end of the magazine 9; and so that when the rod 26 is raised through register-operating distance, the slide 10 11 is forced back with its slot 38 under the open lower end of the magazine 9 to receive one of the coins from the magazine; and then when the rod 26 descends again, automatically, as it does in the regular operation 15 of the register, the slide 11 is pulled forward carrying with it the coin in the slot 38 to fall into the lower chute 21 and travel therefrom into the cup 22 outside the rear of the device. By making the slot 38 20 somewhat longer than the coin, as herein-before alluded to, and causing the slide 11 to travel a distance about equal to the length of this slot, ample time is afforded for the action of gravity on the coin, even though 25 the mechanism is operated with a quick motion as is usual in the operation of a fare register. Also, preferably, the upper side of the slide 11 has in the region of the slot 38 a depression of shorter more abrupt inclination at the front end, and longer gradual inclination toward the rear. This 30 provides for uninterrupted operation of the device when one of the coins that is dropped into the slot 38 is thinner than it should be; since the next coin above will ride over the ends of the slot due to the inclined parts of the recess 39 instead of obstructing the 35 operation of the slide as it would if it engaged square corners at the ends of the slot 38.

The rear side of the magazine 9 has a sight aperture 40 through it down next to the slide, and the back of the upper compartment 3 is partly made up of a transparent plate 41, so that the parts inside the compartment 3 are visible from the rear of the device. The rear side of the hopper 13 is open toward this transparent back-plate 41. Thus, the conductor or fare taker 45 can at all times see whether there be any coins in the magazine 9 or on the trap-door 14.

Constructed as above described, the coins are all placed in the slot 7. The large ones 50 will slide over the opening 12 in the bottom of the chute 8 and fall into the bottom of the magazine 9; but smaller coins will drop through the opening 12 and be carried by the hopper 13 to the trap-door 14.

60 This construction is especially adapted for collection of fares on street cars where a fare of five cents is charged for adults and a fare of three cents for children. The slot 7 and chute 8 are made wide enough to admit the nickel five cent piece but to admit

no larger United States coin; while the opening 12 is made of such width that a copper one cent piece will fall through it. Passengers are provided with the five cent pieces and insert one for each adult fare, and these 70 will travel to the magazine 9; but if a child's fare is paid with three one cent pieces, these all pass to the trap-door 14. The five cent pieces are withdrawn from the magazine 9 into the cup 22 each time a five cent fare is 75 registered, and are thus available to the conductor for use in supplying future passengers with five cent pieces. The one cent pieces, however, are passed into the drawer 18 when the conductor drops the trap-door 80 14 by means of the weighted lever 16 and these one cent pieces are removable only upon opening the door 19 by one who has authority to break the seal. It will be understood, also, that silver ten cent pieces will 85 pass through the opening 12, hopper 13 to the trap-door 14 and thence into the drawer 18, and are removable only by opening the door 19. The deposit of the ten cent pieces is not according to the intended system of 90 operation of the device, and when such a coin is deposited by a passenger, as, of course, will occasionally happen in the payment of two fares when the passenger making the payment does not know of this detail of the system, it will be the duty of the conductor to supply this passenger with two five cent pieces and instruct the passenger to deposit these in this slot 7, which coins will, of course, pass to the magazine 9, and 95 it will also be the duty of the conductor to operate the register twice and thus register these two fares that were paid. In doing so, he will, of course, receive back two five cent pieces from the fare-box; but these 100 will really represent the ten cent piece that passed to the trap-door 14. In this manner, all of the five cent fares will be indicated on the register, which will thus hold the conductor strictly to account for the ten cent pieces which pass into the drawer 18 110 where they are inaccessible to him, as well as the five cent pieces which he has charge of.

Also, should the passenger deposit five one cent pieces for a five cent fare, which coins will, of course, go to the trap-door 14 like the ten cent piece, it will be the duty of the conductor to give the passenger a five cent piece with instructions to deposit it in the slot 7 to pass to the magazine 9; and the 115 conductor will register a five cent fare thereby obtaining from the magazine, one five cent piece.

The balance of one cent pieces found in the drawer 18 will represent the three cent fares which are unregistered and inaccessible to the conductor.

120 It will be understood that the conductor is supplied with an ample number of five cent pieces at the beginning of the run of the 130

car, and is held accountable for this amount of money; and he supplies passengers with these five cent pieces in exchange for currency of various denominations, and in combination with other currency of various denominations in such a manner that under ordinary circumstances and with the initial supply of five cent pieces properly calculated, he will have a sufficient supply of the five cent pieces through the return of one of these for each five cent fare which he registers.

At the same time, it is not possible for a dishonest person to take out a greater value than is put into the fare-box. The insertion of a slug in this machine will avail the person nothing, but on the contrary will cost him five cents in order to get the slug out of the machine again, since it will be necessary to register that amount on the fare register; and those coins, the value of which is not registered on the fare register, do not pass to the magazine 9 at all, and can be taken from the machine only by a person authorized to break the seal 20.

It will thus be seen that the use of my improved device occasions no additional inconvenience either to the passenger or conductor, but that deposit of the coin in the slot 7 by the passenger insures against any dishonest practice by the conductor.

To insure against withdrawal of the coins back through the slot 7, I prefer to provide the tongue 42 extending part of the way across the top of the magazine 9 from the bottom of the chute 8 and to provide the opening 12 with a V-shaped end 42' up toward the slot 7. By this means there are provided at the abrupt turns across which the coin would have to be dragged by a slender instrument, such as a wire or the like, a sharp crotch (in the case of the top of the magazine 9, two such crotches at opposite sides of the tongue 41) into which the slender pulling instrument will ride, and in which the coin will become lodged and prevent further pulling.

Having fully described my invention, what I claim as new and desire to secure by Letters Patent is:

1. In a fare-box, a casing having a coin-receiving opening in its upper part, an upper chute extending downwardly from said opening and inclined toward one side of said casing, an upright magazine into the top of which said chute leads, a guideway having an opening communicating with the bottom of said magazine, a lower chute communicating through the bottom of said guideway out of line with said magazine and having an opening to the exterior of said casing, a slide sliding in said guideway, and having a slot, an operative connection to said slide extending outside said casing to engage with part of a fare-registering mechanism, where- 65 by said slide has its slot brought under said

magazine and then brought back over said lower chute each time the value of a coin is registered by said mechanism, said upper chute having an opening in its lower side, narrower than the coins delivered to said 70 magazine, whereby only smaller coins are delivered through this opening, a receptacle inclosed in said casing under said opening in said upper chute, means for controlling delivery of said smaller coins to said receptacle, and an operative connection to this means extending outside said casing for manual operation.

2. In a fare-box, a casing having an interior horizontal partition dividing it into an upper compartment and a lower compartment, and having a slot in the upper part of its upper compartment, an upper chute extending downwardly from said opening and inclined downward toward one side of 85 said upper compartment, an upright magazine into the top of which said chute leads, a guideway fixed on said horizontal partition and supporting said magazine, and having an opening communicating with the bottom of said magazine, a lower chute opening upwardly into the bottom of said guideway out of line with said magazine and extending backwardly and downwardly, and having an opening through one of the walls of 90 said lower compartment, a slide sliding in said guideway, and having a slot, a bell-crank, a fixed fulcrum for said bell-crank, means connecting one arm of said bell-crank to said slide, and means whereby the other 95 arm of said bell-crank engages with part of a fare registering device, whereby the registry of the value of one of the coins entering said magazine causes said slide to bring its slot under said magazine and then bring said 100 slot back over said lower chute, delivering one of said coins from said magazine out through said lower chute.

3. In a fare-box, a casing having an interior horizontal partition dividing it into an upper compartment and a lower compartment, and having a slot in the upper part of its upper compartment, an upper chute extending downwardly from said opening and inclined downward toward one side of said 110 upper compartment, an upright magazine into the top of which said chute leads, a guideway fixed on said horizontal partition and supporting said magazine, and having an opening communicating with the bottom of said magazine, a lower chute opening upwardly into the bottom of said guideway out of line with said magazine and extending backwardly and downwardly, and having an opening through one of the walls of said 115 lower compartment, a slide sliding in said guideway, and having a slot, an operative connection to said slide extending outside said casing to engage with part of a fare 120 registering mechanism, whereby said slide 125 has its slot brought under said

has its slot brought under said magazine and then brought back over said lower chute each time the value of a coil is registered by said mechanism to deliver a coin of such 5 value out through said lower chute, said upper chute having an opening in its lower side, said horizontal partition having an opening through it, a trap-door swung upwardly to close this opening, means connected to said trap-door and extending outside said casing for swinging said trap-door 10 downwardly, a hopper under said opening in said upper chute and leading to said trap- door, and a receptacle inclosed in said lower compartment under said trap-door, said 15 opening in said upper chute being narrower than the coins to be delivered to said magazine, whereby only smaller coins are delivered to said hopper and trap-door and from there into said receptacle in said lower compartment. 20

GEORGE K. HUNDLEY.
